UNITED STATES PATENT OFFICE.

HERMANN A. WENDE, OF BUFFALO, NEW YORK.

BELL-RINGING MECHANISM.

1,349,400.

Specification of Letters Patent. Patented Aug. 10, 1920.

Application filed June 22, 1914, Serial No. 846,491. Renewed January 5, 1920. Serial No. 349,637.

To all whom it may concern:

Be it known that I, HERMANN A. WENDE, a citizen of the United States, residing at Buffalo, in the county of Erie and State 5 of New York, have invented new and useful Improvements in Bell-Ringing Mechanism, of which the following is a specification.

This invention relates to a mechanism for ringing bells, chimes or the like and has for 10 its object to produce a mechanism for this purpose which is efficient and reliable in its operation, which is capable of producing either a comparatively loud or soft tone, and which rings the bells at regular intervals.

In the accompanying drawings: Figure 1 is a front elevation of a bell ringing mechanism embodying the preferred form of my improvements. Fig. 2 is a vertical longitudinal section of the same, on an enlarged scale, taken in line 2—2, Fig. 1. Fig. 3 is a fragmentary vertical transverse section, on an enlarged scale, taken in line 3—3, Fig. 2. Fig. 4 is a fragmentary vertical transverse section taken in line 4—4, Fig. 2 looking rearwardly. Fig. 5 is a similar view taken in line 5—5, Fig. 2, looking forwardly. Fig. 6 is a fragmentary horizontal section taken in line 6—6, Fig. 5. Fig. 7 is a 20 fragmentary top plan view of the machine, partly in section. Fig. 8 is a fragmentary vertical longitudinal section of the machine similar to Fig. 2 and showing the means whereby the stroke of the bell hammer operating mechanism may be shortened for the 25 purpose of modulating or softening the tone of the bell. Fig. 9 is a vertical transverse section of the same, on an enlarged scale, taken in line 9—9, Fig. 8. Fig. 10 is a fragmentary elevation of the means for 30 softening the sound of the bell. Fig. 11 is a fragmentary horizontal section taken in line 11—11, Figs. 8 and 9. Fig. 12 is a fragmentary vertical longitudinal section 35 of the machine taken in line 12—12, Fig. 1 and showing those parts thereof which are 40 designed to produce a continuous tolling of a bell. Fig. 13 is a plan view of the switch mechanism associated with this bell 45 tolling mechanism whereby the electric circuit controlling the operation of this mechanism is automatically opened and closed.

Similar characters of reference indicate 50 corresponding parts throughout the several 55 views.

1 represents the main frame of the bell ringing mechanism which may be of any suitable construction to support the working parts thereof. Arranged in the central part of this frame and in a transverse row 60 are a plurality of upright bell operating rods or members 2 which are capable of vertical movement and guided at their upper and lower ends in suitable openings formed in fixed upper and lower 65 horizontal transverse guide bars 3, 4 mounted on the main frame while their intermediate parts slide in openings formed in an intermediate guide bar 5 arranged horizontally and transversely of the 70 machine and mounted on the main frame. Associated with each one of these operating rods is a bell 6 which is adapted to be sounded by a device which is operated by the downward movement of the respective 75 rod. When this bell forms one member of a set of chimes the same may be mounted on a support 7 so that it is relatively stationary, as shown in Fig. 8, and the same may be sounded by means of a hammer or 80 tongue 8 adapted to strike the inner side of the same. This hammer is mounted on the upper end of one arm 9 of a vertically swinging elbow lever, the other arm 10 of which is connected by means of a chain 11 or otherwise with the upper end of one of the bell operating rods 2. Upon pulling the operating rod 2 downwardly the bell hammer connected with the upper end thereof is caused to swing upwardly and inwardly 85 against the inner side or mouth of the bell and ring the same. The weight of the bell hammer when swinging away from the bell operates to lift the operating rod and hold it in its elevated position, the movement 90 of this rod in an upward direction being limited and also made adjustable by means of adjusting screw nuts 12 mounted on the lower screw threaded end of this rod and adapted to engage with the underside of 95 the lower guide bar 4, as shown in Fig. 2. That portion of my improved bell ringing mechanism adapted to operate the same for playing a tune or melody is shown in Figs. 100 1—11 and is constructed as follows:

13 represents a plurality of horizontal longitudinal operating bars which are arranged in a transverse row in the front part of the main frame and each of which is operatively associated with one of the bell 110

operating rods by extending the rear part of the respective operating bar through a slot 14 which is preferably formed between the side of the companion operating rod and a 5 loop 15 secured to the adjacent side of this operating rod, as shown in Figs. 2, 5, 7 and 8. Between its front and rear ends each of the operating bars is so mounted that the same is capable of a limited vertical reciprocating movement and also turning horizontally about a vertical axis. The preferred means for this purpose which are shown in the drawings comprise an upright guide rod 16 which passes through guide 10 openings formed in horizontal transverse guide bars 17, 18 arranged above and below the operating bar and mounted on the main frame, the guide rods of the several operating bars being arranged in a transverse 15 row in the machine. In order to hold each of the operating bars reliably in a horizontal position with reference to its upright guide rod the lower end of each of these rods is connected with the front part of the 20 respective operating bar by means of an inclined brace 19, as shown in Figs. 2 and 8, thereby producing in effect a triangular structure which is very rigid and prevents vertical displacement of the operating bar 25 relatively to its guide rod. Each of the operating bars and its guide rod are yieldingly held in an elevated position, preferably by means of a spring 20 connected at its lower 30 end with a rearward extension of the lower end of the brace 19 while its upper end is connected with a horizontal transverse bar 21 arranged in rear of the upper part of the guide rod 16 and mounted on the main frame. In the elevated position of this operating bar its rear end is arranged adjacent to the lower end of the guide slot 14 on the companion bell operating rod while the latter is in its elevated or inoperative position, as shown in Figs. 2 and 5. Upon depressing the operating bar while the parts 35 are in this position, its rear end or arm engages with the lower end of the slot 14 in the respective bell operating rod and depresses the latter, so that the companion bell 40 hammer strikes a blow against the bell associated therewith. As soon, however, as the operating bar is again released the same is raised by means of its spring 20 into its uppermost position.

45 In order to cushion the upward or return movement of the operating bar and associated parts and prevent not only undue noise but also jarring and wear of the machine, means are provided which preferably 50 comprise a piston or plunger 22 formed by the upper end of the guide rod 16 and working in a barrel or cylinder 23 mounted on the adjacent part of the main frame. The plunger 22 is provided with a downwardly dished 55 cup-shaped packing 24 so that as this plun-

ger descends in the cylinder or barrel 23 the air will be free to pass this packing into the upper part of the barrel and thereby avoid retarding the downward movement of the operating bar, but during the upward movement of the guide rod the cup-shaped packing presses the air upwardly in the cylinder and slowly outwardly through an opening or port 25 in the upper end of the barrel. A small quantity of air also enters the barrel through the port 25 during the downward movement of the plunger. This port is covered more or less to regulate its capacity, preferably by a bendable copper disk 26 secured to the top of the barrel over the port 25 and adapted to be moved toward or from the same to vary its effective area. The upward movement of each operating rod is limited by a stop device which is preferably made adjustable so as to permit of accurately timing the sounding of the respective bell. The preferred means for this purpose which are shown in Figs. 2 and 5 comprise a screw bolt 27 having its lower threaded part engaging with a threaded opening 28 in the head at the upper end of the barrel while its upper threaded part passes loosely through an opening 29 arranged in a supporting bar 30 mounted on the main frame and arranged over the upper end of the cushion barrel, a screw nut 31 arranged upon the central threaded part of the bolt 27 and engaging with its underside against the top of the barrel head through the medium of the valve disk 26 while its upper side bears against the underside of the supporting bar 30, and an upper screw nut 32 arranged on the threaded upper part of the bolt 27 and engaging with the upper side of the supporting bar 30. At the end of the upward stroke of the operating bar the upper side of the plunger 22 engages with the lower end of the stop screw 27, thereby arresting the further upward movement of the stop bar. Upon loosening the screw nuts 31, 32 the bolt 27 may be screwed up or down in the head of the barrel for changing the position vertically of the lower end of the bolt 27 and thus varying the position at which the operating bar comes to rest during its upward movement by engagement of the upper end of the plunger 22 with the adjusting screw 27. After the screw 27 has been adjusted to the desired position the same is again held in place by tightening the screw nuts 31, 32 against opposite sides of the supporting bar 30.

The depression of each one of the operating bars 13 and the respective operating rod associated therewith is effected by engagement with the upper side of the rear end or arm of this bar by one of a plurality of tappets 33 which project laterally outward at intervals from an endless carrier or belt 34 which is preferably constructed in

the form of a chain and passes with its upper and lower turns around upper and lower sprocket or supporting wheels 35, 36 forming a vertical operative front stretch 5 of this belt and a vertical inoperative rear stretch. A row of such tappet carrying belts is arranged transversely in the rear part of the main frame behind the operating bars and rods, the several upper sprocket 10 wheels 35 being mounted on an upper horizontal shaft 37 which is journaled transversely in suitable bearings on the upper part of the main frame while the lower sprocket wheels 36 are mounted on a horizontal shaft 38 turning in suitable bearings 15 on the lower part of the main frame. When the machine is in operation, the tappet belts are moving constantly in a direction in which the front operative stretches of the 20 same descend and the inoperative stretches thereof ascend. Motion may be imparted to these tappet belts in any suitable manner, the means for this purpose shown in the drawings consisting of an electric motor 39 25 mounted on the right hand side of the main frame and having its shaft 40 provided with a gear pinion 41 which meshes with a gear wheel 42 on the corresponding end of the upper shaft of the tappet belts. The opposite 30 end of the upper tappet shaft is preferably provided with a fly wheel 43 so as to cause these belts to run uniformly notwithstanding that the load placed upon the same may be irregular.

35 In the normal inoperative position of each operating bar its rear end or arm is arranged on one side of the path of the tappets of the companion tappet belt, as shown in Fig. 7, in which position of the 40 parts the tappet belt moves idly and does not affect the position of the companion operating bar and the bell associated therewith. When, however, the operating bar is turned horizontally about the guide rod 16 45 as an axis, so that the rear end of this bar is shifted into the path of the companion set of tappets, the next following tappet immediately above the operating bar will engage with the upper side thereof and 50 move the same downwardly together with the operating rod connected therewith and cause the hammer associated therewith to strike the companion bell. The operating bar remains in engagement with the respective tappet a sufficient length of time to produce the desired stroke of the bell hammer and then moves laterally out of engagement from the operative tappet so as to permit the operating bar to again rise under the 55 lifting action of the spring 20 as the same drops away from the bell. The tappets of the respective tappet belt engage with the companion operating arm on the vertical operative stretch of this belt so that these 60 tappets remain fully in engagement with this operating bar during the entire stroke of the bell hammer and therefore produce an effective blow of the same against the bell. The tappets on the tappet belt are also arranged comparatively close together 70 so that the operating arm will be engaged by a tappet immediately after the operating bar is moved into the path of the tappets, thereby causing the bell to be sounded promptly without any appreciable loss of 75 time and causing the chimes to be rung with practical regularity or uniformity.

Each of the operating bars when turned horizontally into an inoperative position or out of the path of the companion set of 80 tappets is positively held in this position by means which preferably comprise a vertically swinging detent catch or latch 44 mounted on the front part of the frame and provided with a shoulder 45 on the underside of its free end which engages over the upper end of a detent finger 46 projecting upwardly from the front end or arm of the respective operating bar and preferably forming an upward projection of the re- 85 spective brace.

The front end or arm of each of the operating bars projects forwardly through an upright slot 47 formed between adjacent upright bars on the front part of the main frame. While this bar is in its uppermost 90 position the same is engaged by a pressing device which engages with that side of the operating bar opposite to that which it is engaged by the shoulder of the latch 44 so 95 that when the latter is released from the operating bar the same will be turned in a direction for moving its rear end into the path of the companion set of tappets and sounding the companion bell. This pressing device 100 preferably consists of an upper inclined arm 48 which is pivoted on the adjacent part of the main frame so as to swing transversely of the machine about a horizontal axis while its upper part is pressed against 105 the front part of the operating bar by a spring 49 connecting this presser arm with the adjacent part of the main frame. The release of the latch 44 is preferably effected by electrical means those shown in the drawings consisting of an electro-magnet 50 mounted on the main frame and having its poles arranged opposite an armature 51, attached to the upperside of said latch. The circuit of this electric magnet contains a 110 battery 52 or other source of electric energy and this circuit is adapted to be closed by a switch which may be variously constructed but as shown in Fig. 2 preferably comprises a fixed terminal or contact 53 connected with 115 one side of said electric circuit and a movable terminal or contact 54 connected with the other side of this circuit and adapted to engage with the fixed contact for closing the circuit. Upon closing this circuit, the 120 125 130

electro-magnet becomes energized and lifts the latch 44, thereby releasing the front end of the respective operating bar and permitting the spring 49 to move the upper presser arm 48 and the front end of the operating bar horizontally in a direction which will cause the rear end of this bar to move into the path of the tappets, thereby causing the next following tappet to engage with the respective operating bar and depress the same together with the operating rod associated therewith and ring the companion bell. As shown in Fig. 2, the fixed contact 53 is mounted on the upper part of a stationary supporting bar 55 of insulating material and the movable contact 54 is arranged at the upper end of a vertically swinging arm 56 which is connected by means of a coil spring 57 with this supporting bar. This last mentioned spring operates constantly to swing the movable contact 54 away from the fixed contact 53, the movement in this direction being limited by means of a staple 58 bracing this arm and secured to the supporting bar 55 which staple also serves as a guide for this arm. The several switches of the electro-magnets 50 associated with the latches which control the operating bars are preferably arranged in a row and each switch arm 56 is arranged in front of one of the hammers 59 of a piano or similar key board mechanism, so that upon depressing a particular key the corresponding hammer thereof will strike the switch arm 56 and move the same rearwardly for closing the circuit of the particular electro-magnet 50 which controls the ringing of the bell corresponding to that particular key. This key board mechanism is not shown in the drawings inasmuch as it may be of the usual and well known kind now commonly found in pianos. It is preferable to use this ringing apparatus in connection with such a key board, inasmuch as it permits of playing the chimes by merely operating the key board in the ordinary manner of playing a tune on a piano or organ. If desired, however, the circuits of the several electro-magnets 50 may be closed by a switch mechanism of any other suitable construction.

After the operating bar has been depressed a sufficient distance to cause the bell hammer to ring the bell associated therewith, the operating bar is turned horizontally in the opposite direction for disengaging its rear end from the respective tappet which engages the same. This is preferably accomplished by engaging the front end of the operating bar with a lower pressing device which is arranged at the lower end of the slot 47 in which the front end of the operating lever moves and which serves to shift the operating bar in a direction opposite to that in which it was shifted by the action of the spring 49 of the presser arm 48. This

lower pressing device preferably comprises an inclined pressing arm 60 pivoted at its upper end on the adjacent part of the main frame so as to swing transversely about a horizontal longitudinal axis, and a spring 61 connecting the lower end of the lower presser arm 60 with the adjacent part of the frame. The pin 62 connecting the spring 61 with the presser arm is preferably so arranged that it serves as a stop which engages with the adjacent wall of the slot 47 in which the operating arm moves and thereby limits the swinging movement of the lower presser arm and the action of the spring 61, as shown in Fig. 1. The instant the lower presser arm 60 turns the operating bar horizontally sufficiently to disengage its rear end from the operative tappet of the tappet belt the spring 20 instantly raises the operating bar and the parts associated therewith. During the last portion of this upward movement of the operating bar its front end engages with the inclined upper presser arm 48 and deflects the same slightly so as to strain its spring 49, and the upper end of the detent finger on the operating arm re-engages the shoulder of the companion latch 44 which is now in its depressed position, thereby holding the operating bar in its inoperative position preparatory to performing another cycle of operations.

Means are provided for holding the operating bar in the path of the tappets during the downward movement of this bar a sufficient length of time to insure a full stroke of the bell hammer against the bell and also to hold this bar in its inoperative position during its upward or return stroke so as to prevent interference of the downwardly moving tappets therewith and also insure engagement of the detent finger of the operating bar with the latch 44. For this purpose an upright guide is arranged adjacent to the right hand side of the rear part of each operating bar this guide being preferably composed of upper and lower sections 63, 64 and mounted on a transverse supporting plate 65 secured to the adjacent part of the main frame. As each operating bar is turned by the spring of the upper presser bar 48 horizontally in a direction for carrying its rear end into the path of the companion tappets this rear end swings over the upper end of the upper guide section 63. As the next following tappet engages with the upper side of the operating arm and presses the same downwardly an inclined face 66 on the underside or edge of the rear end of the operating arm engages with the correspondingly inclined face 67 at the upper end of the upper fixed guide section 63, as shown in Fig. 9, thereby causing the rear end of the operating bar during its continued downward movement while in engagement with the underside of a tappet to

be forced laterally to a greater extent underneath the respective tappet so that these parts engage with each other over a greater surface and insure a more reliable action of 5 the bell ringing mechanism. The rear end of the operating bar is thus held underneath the active tappet by the front faces of the upper and lower guide sections 63, 64 past which this end of the operating bar slides 10 during this time until it reaches the lower end of the lower guide section. At the same time that the rear end of the operating bar passes below the lower end of the lower guide section 64 its front end engages with 15 the inclined lower presser arm 60 and is shifted laterally by the same so that the rear end of the operating bar is disengaged from the active tappet and moved underneath the lower end of the lower guide section 64 and 20 in line with the rear side thereof. This operating bar is now raised by the action of its spring 20 and during this upward movement its rear end slides upwardly past the rear sides of the lower and upper guide sections 25 63, 64 and is thereby held positively out of the path of the tappets so that but one sounding of the bell is insured. The guide sections hold the operating bar in this turned position until the front end of this 30 bar engages the upper presser arm and the detent finger has reengaged the shoulder of the latch 44, this reengagement of this finger and latch occurring during the last part of the upward movement of the operating bar 35 and just before the rear end of the operating bar passes above the upper edge of the upper guide section 63.

For convenience in setting up the machine the upper presser arms 48 are provided with 40 upwardly facing shoulders 68 which are adapted to engage with the lower edges of the front ends of the operating bars and hold the same together with the associated parts in an elevated position, but these 45 shoulders serve no purpose after the machine is set up.

When it is desired to modulate or soften the tone or sound of the bell when the same is struck by the hammer, means are provided for shortening the downward throw of each operating rod and thereby reducing 50 the intensity or power of the blow of the bell hammer against the bell. The preferred means for this purpose which are 55 shown in Figs. 2, 8 and 9 are constructed as follows:

The upper guide section 63 is fixedly mounted on the supporting plate 65 while the lower guide section 64 is pivotally 60 mounted at its lower end on this plate so as to be capable of swinging transversely about a horizontal longitudinal axis so that this lower guide section may be either brought into a position in which it forms a downward extension of the upper guide section 65

63, as shown by full lines in Fig. 9, or the same may be swung laterally away from the upper guide section, as shown by dotted lines in the same figure, in which last mentioned position of the lower guide section 70 the same is inoperative and only the upper guide section is utilized to control the operating bar. The lower guide section is yieldingly held in line with the upper guide section when the same is not required for 75 use but positively locked in line with the upper guide section when the same is in use. The yielding means for this purpose preferably consists of a spring 70 secured at one end to a lug 71 on the supporting plate 80 and bearing against the rear side of the lower guide section beyond the place where the latter is engaged by the rear end of the companion operating bar. The means for holding the lower guide section rigidly in line with the upper guide section comprise a horizontally swinging latch or catch 72 which is pivoted on the adjacent part of the supporting plate 65 and provided with a shoulder 73 which is yieldingly 85 held in engagement with a pin, projection or shoulder 74 on the rear edge of the lower guide section, as shown in Figs. 8 and 11, by means of a spring 75 bearing at one end against this latch and at its other end against a stationary part. This catch or latch may be released or disengaged from the pin of the lower guide section in various ways but this is accomplished by electrical means which comprise an electro-magnet 76 mounted on the supporting plates 65 and having its poles arranged opposite an armature 77 on the back of the latch 72, and a switch plug or member 78 adapted to connect two contacts 79, 80 for the purpose of closing an electrical circuit which includes the electro-magnet 76 and a battery or electric generator 152, as shown in Fig. 8. When the switch member 78 is withdrawn so as to break the circuit across the contacts 79, 80, the electro-magnet 76 is deenergized, thereby permitting the latch 72 to lock the lower guide section rigidly in its operative position in which it forms a downward continuation of the upward guide section 105 so that when the companion operating bar is moved downwardly by one of the corresponding sets of tappets, the rear end of this operating bar will be compelled to travel downwardly along the entire front faces of the upper and lower guide sections before the rear end of this operating bar can be moved laterally out of engagement from the respective tappet by the pressure of the lower presser arm 60 engaging the front end of the operating bar and turning the same so that its rear end moves laterally across the lower end of the lower guide section immediately upon passing below the same. A long downward pull on the operating rod 110

is thus produced which causes the bell hammer to swing with a powerful or heavy stroke toward the bell and strike the same for producing a loud sound. Upon shifting 5 the switch member 78 so as to connect the contacts 79, 80, the circuit through the electro-magnet 76 will be closed so that the latter is energized and releases the lower guide section 64 by withdrawing the latch 72 out of engagement from the pin 74. When the lower guide section is thus 10 unlocked by the latch 72 the rear end of the operating bar, after it moves downwardly along the front side of the upper guide section under the downward pressure of a tappet and clears the lower end of this guide section, is pressed laterally out of engagement from the operative tappet by the lower presser arm 60 and caused to move laterally 15 rearward across the lower end of the upper guide section 63 and then moved vertically upward along the rear side of this section to a position above the upper end thereof under the action of its spring 20. While 20 the rear end of the operating bar thus swings laterally past the lower end of the upper guide section, the lower guide section is deflected in opposition to the resilience of its spring 70, but when the operating arm 25 has again cleared this lower guide section this spring again returns the same to its normal vertical position in which it is aligned with the upper guide section. The movement of the lower guide section under the 30 action of its spring 70 may be limited in various ways, for instance, as shown in Fig. 9 by lapping the upper end of the lower guide section past the lower end of the upper guide section. When the operating bar only moves downwardly and upwardly 35 around the upper guide section, the downward stroke of the companion operating rod is shortened, thereby producing a less vigorous pull on the bell hammer and causing the same to strike a lighter blow against the corresponding bell.

In order to further differentiate the effect of the hammer blow against the bell for producing either a loud or soft tone, means are provided whereby the bell hammer may strike either directly against the bell for 40 producing a loud sound during a long pull of the operating rod or a cushioning member may be interposed between the bell 45 and the bell hammer during a short pull of the operating rod so that the bell hammer engages indirectly with the bell and therefore produces a modulated or softer tone. The preferred means for accomplishing this 50 purpose which are shown in Figs. 8 and 10 comprise a cushion member 81 preferably consisting of a strip of leather which is connected at its lower end by means of a link 82 with the upper end of the companion operating rod while its upper end is con-

nected with an open yoke 83, the latter being in turn connected by a spring 84 with a fixed support 85 which is preferably located centrally within the underside of the crown of the bell so that the cushioning 70 strip is arranged on the inner side of the bell.

When a short downward stroke of the operating rod is produced the cushioning strip 81 is also pulled downwardly in opposition to the spring 84 but only to a moderate extent, so that the same remains in the path of the bell hammer and causes the latter to strike the bell indirectly by reason of the cushioning strip being interposed between these parts at this time, thereby producing a soft or modulated tone of the bell. When, however, a long downward pull of the operating rod on the bell hammer is produced the cushion strip is pulled downwardly a greater extent and caused to clear 85 the path of the bell hammer so that the latter strikes directly against the bell through the open yoke 83 above the cushion strip, thereby producing a loud tone.

When it is desired to toll a bell continuously without requiring continuous manipulation of the key board my improved bell ringing mechanism is organized as shown in Figs. 12 and 13. Inasmuch as only one of such bells is usually required this mechanism can be incorporated in the same machine which operates to ring a set of chime bells. This bell tolling mechanism is constructed as follows:

86 represents a horizontal rock shaft upon which the tolling bell 87 is mounted and which is provided with a drum or wheel 88 the periphery of which is connected by a line, cord, cable or other flexible member with the upper end of an operating rod 89 105 similar to the operating rods used in connection with the chime ringing mechanism. The lower part of this tolling operating rod is guided similar to the chime operating rods 2 and is provided with a loop 90 which receives the rear end of an operating bar 91 secured to a vertically movable guide rod 92 which latter is guided, adjusted and cushioned in its vertical movements by the same means as those shown in Fig. 2 with reference to the guide rods 16. This operating bar and the parts associated therewith are yielding held in an elevated position by means of a spring 93. The depression of the operating bar is effected by one of a series of tappets 94 similar to those shown in Fig. 2, the operating bar is held turned in a position in which its rear end is arranged above the rear side of a vertical guide 95 by means of a latch 96 engaging with a detent finger 97 on the front end of the operating bar and an electro-magnet 98 is adapted to attract an armature 99 on the latch 96 similar to the construction shown in Fig. 3, and an upper and lower pressing device is however 130

associated with the front end of this operating bar similar to the upper and lower presser bars shown in Figs. 1 and 2. The guide 95 in the tolling mechanism is preferably made in one continuous piece instead of being made in sections. 100 represents a segmental electric contact mounted on a fixed support adjacent to the tolling bell and concentric therewith and 101 is a movable flexible contact arm mounted on the adjacent part of the bell shaft and adapted to engage with the fixed contact 100 during the rocking of the bell in a forward direction but to be disconnected therefrom as the bell swings in the opposite direction. These contacts 100-101 form part of an electric circuit which includes the electromagnet 98 and a battery 102 or other electric generator. This circuit also contains a make and break device or switch which comprises an upper contact 103 mounted on a relatively fixed support and a lower contact 104 which is carried by the companion operating bar 91. Adjacent to the segmental fixed contact 100 is arranged a segmental row of oblique guide plates 105 which are free at their inner ends and supported on a fixed bracket 106 at their outer ends. When the bell is at rest the contact arm 101 is arranged adjacent to the segmental contact 100 but out of engagement therewith and also adjacent to the front end of the row of guiding or deflecting plates 105, as shown in Figs. 12 and 13. The initial forward rocking movement of the bell is effected by closing the circuit containing the battery 102 and the electro-magnet 98 by hand this being effected by engaging the contacts 107, 108 of a switch the members of which are connected across the circuit of the battery 102 and electro-magnet 98, but thereafter the circuit of the magnet is opened and closed intermittently by the operation of the switch contacts 100, 101 and the switch contacts 103, 104. Assuming that the bell is at rest and it is desired to toll the same, the first operation is to engage the contacts 107, 108 of the starting switch, thereby closing the circuit through the electro-magnet 98 and causing the latter to lift the latch 96 out of engagement from the companion detent finger and permit the rear arm of the respective operating bar to swing laterally underneath the next following tappet associated therewith. As the latter descends and carries the operating bar downwardly with it this bar slides past the front side of the guide 95 and upon reaching the lower end of this guide this operating bar is moved across this lower end and out of engagement from the respective tappet and then slides upwardly along the rear side of this guide to its uppermost position in the same manner as described with reference to the construction in Fig. 2. During the last portion of

the downward movement of the operating bar the same strikes the lower end of the loops 90 causing the operating rod 89 to be pulled downwardly, the wheel 88 to be turned and the bell 87 to be swung forwardly or in the direction of the arrow indicated in Fig. 12. During the downward movement of the tolling operating bar the switch contacts 103, 104 are separated so as to break the circuit through the electromagnet 98 but during the last part of the upward stroke of the operating bar under the action of its spring 93 the contacts 103, 104, are again engaged. During the return or backward swing of the bell the same, owing to its weight, passes rearwardly beyond its central or neutral position so that the contact arm 101 slips past the rear ends of the set of oblique guide plates 105. After the bell has completed its backward swing 85 ing movement and begins its next forward stroke, the contact arm 101 is guided by the adjacent inclined guide plate 105 laterally toward the fixed segmental contact 100 and caused to engage the same, thereby again closing the circuit which includes the battery 102 and the electro-magnet 98 and causing the operating bar 91 to be released and swing with its rear end horizontally into the path of the tappets so that the latter as 90 they descend produce another working downward stroke of the operating bar and an operative or effective forward stroke of the bell. During the first part of the downward movement of the operating bar 91 the electric circuit is again broken between the contacts 103, 104 notwithstanding that this same circuit remains closed temporarily by engagement of the contacts 100, 101. In this manner the bell 87 continues to toll intermittently so long as the motor is in operation and moves the tappets inasmuch as the electric circuit for operating the electromagnet 98 is closed when the operating bar reaches the end of its upward stroke and the tolling bell effects the initial portion of its forward stroke, while the circuit is broken at all other times, thereby automatically tolling the bell 87 at regular intervals.

My improved bell ringing device is not only efficient in operation but the same also permits the bells to be rung with regularity and precision.

I claim as my invention:

1. A bell ringing mechanism comprising an operating member connected with the bell, an endless power operated shifting member having a plurality of tappets, and means for coupling one or another of said tappets directly with said operating member.
2. A bell ringing mechanism comprising an operating rod connected with a bell sounding device and having a longitudinal slot, an operating bar arranged in said slot so as to move downwardly with said rod but

capable of moving upwardly independently thereof, and movable tappets engaging said bar for shifting the latter and said rod.

3. A bell ringing mechanism comprising

5 an operating bar operatively connected with a bell sounding device, a movable belt provided with a plurality of tappets, and means for moving said bar into the path of said tappets for causing said bar and the sounding device connected therewith to be actuated.

10 4. A bell ringing mechanism comprising an operating bar operatively connected with a bell sounding device, a movable belt having an operative stretch arranged adjacent to said bar and provided with a plurality of laterally projecting tappets, and means for shifting said bar into and out of the path of said tappets for causing said bar and the sounding device connected therewith to be actuated.

15 5. A bell ringing mechanism comprising an operating member which is operatively connected with a bell sounding device, a movable power operated element having a plurality of tappets, and means for causing the movement of said tappets to be transmitted directly to said member for operating said bell sounding device and causing the bell to sound.

20 6. A bell ringing mechanism comprising an operating bar operatively connected with a bell sounding device, a movable tappet which shifts said bar directly to operate the bell sounding device, means for moving said tappet into engagement with said bar for causing said sounding device to be operated, and out of the path of said bar for stopping the operation of said sounding device, 40 and means for guiding said bar to permit the same to move with said tappet.

25 7. A bell ringing mechanism comprising an operating bar operatively connected with a bell sounding device, a movable tappet, a guide rod which supports said bar and is capable of turning transversely and also sliding lengthwise, means for turning said bar into and out of the path of said tappet, and a spring operating to move said bar in a direction opposite to the movement of said tappet.

30 8. A bell ringing mechanism comprising an operating bar operatively connected with a bell sounding device, a movable tappet, a guide rod which supports said bar and is capable of turning transversely and also sliding lengthwise, means for turning said bar into and out of the path of said tappet, a spring operating to move said bar in a direction opposite to the movement of said tappet, and means for cushioning the movement of said bar under the action of said spring.

35 9. A bell ringing mechanism comprising an operating bar operatively connected with

a bell sounding device, a movable tappet, a guide rod which supports said bar and is capable of turning transversely and also sliding lengthwise, means for turning said bar into and out of the path of said tappet, 70 a spring operating to move said bar in a direction opposite to the movement of said tappet, and means for cushioning the movement of said bar under the action of said spring comprising a plunger arranged on said guide rod, and a barrel which receives said plunger and which is provided with an air escape opening.

10. A bell ringing mechanism comprising an operating bar operatively connected with a bell sounding device, a movable tappet, a guide rod which supports said bar and is capable of turning transversely and also sliding lengthwise, means for turning said bar into and out of the path of said tappet, 85 a spring operating to move said bar in a direction opposite to the movement of said tappet, and an adjustable stop for limiting the return movement of said operating bar under the action of said spring.

90 11. A bell ringing mechanism comprising an operating bar operatively connected with a bell sounding device, a movable tappet, a guide rod which supports said bar and is capable of turning transversely and also sliding lengthwise, means for turning said bar into and out of the path of said tappet, a spring operating to move said bar in a direction opposite to the movement of said tappet, means for cushioning the movement 100 of said bar under the action of said spring, comprising a plunger arranged on said guide rod, and a barrel which receives said plunger and which is provided with an air escape opening, and an adjustable stop device for limiting the return movement of said bar and associated parts under the action of said spring comprising a support having an unthreaded opening, an adjusting screw arranged in said unthreaded opening and engaging with a threaded opening in the head of said barrel, a screw nut arranged on said screw between said barrel and one side of said support, and a screw nut arranged on said screw and engaging with the opposite 115 side of said support.

12. A bell ringing mechanism comprising an operating bar operatively connected with a bell sounding device, a movable tappet, and means for moving said bar into the path 120 of said tappet for causing sounding of said sounding device and out of the path of said tappet for causing said sounding device to stop sounding, comprising a latch for holding said bar out of the path of said tappet, 125 an electro-magnet for releasing said latch from said bar, and means for moving said bar into the path of said tappet when released from said latch.

13. A bell ringing mechanism comprising 130

- an operating bar operatively connected with a bell sounding device, a movable tappet, and means for moving said bar into and out of the path of said tappet comprising a latch 5 for holding said bar out of the path of said tappet, an electro-magnet for releasing said latch from said bar, means for moving said bar into the path of said tappet when released from said latch, comprising an inclined presser arm pivotally supported in the path of said bar, and a spring operating to press said arm against said bar in a direction to move the same into the path of said tappet.
- 10 14. A bell ringing mechanism comprising an operating bar operatively connected with a bell sounding device, a movable tappet, and means for moving said bar laterally into the path of said tappet for causing sounding 20 of said sounding device and out of the path of said tappet for causing said sounding device to stop sounding, comprising a latch for holding said bar laterally out of the path of said tappet, an electromagnet for releasing said latch from said bar, means for moving said bar into the path of said tappet when released from said latch, and means for moving said bar out of the path of said tappet at the end of its operative stroke.
- 25 15. A bell ringing mechanism comprising an operating bar operatively connected with a bell sounding device, a movable tappet, and means for moving said bar laterally into the path of said tappet for causing sounding 30 of said sounding device and out of the path of said tappet for causing said sounding device to stop sounding, comprising a latch for holding said bar laterally out of the path of said tappet, an electromagnet for releasing said latch from said bar, means for moving said bar into the path of said tappet when released from said latch, means for moving said bar out of the path of said tappet at the end of its operative stroke.
- 35 16. A bell ringing mechanism comprising an operating bar operatively connected with a bell sounding device, a movable tappet, and means for moving said bar laterally into the path of said tappet for causing sounding 40 of said sounding device and out of the path of said tappet for causing said sounding device to stop sounding, comprising a latch for holding said bar laterally out of the path of said tappet, an electromagnet for releasing said latch from said bar, means for moving said bar into the path of said tappet when released from said latch, means for moving said bar out of the path of said tappet at the end of its operative stroke.
- 45 comprising an inclined presser arm arranged in the path of said bar, and a spring operating to press said arm against said bar in a direction for moving the latter out of the path of said tappet.
- 50 17. A bell ringing mechanism comprising an operating bar operatively connected with a bell sounding device, a movable tappet, and means for moving said bar into and out of the path of said tappet comprising a latch 55 for holding said bar out of the path of said tappet, an electro-magnet for releasing said latch from said bar, means for moving said bar into the path of said tappet when released from said latch, comprising an inclined presser arm pivotally supported in the path of said bar, a spring operating to press said arm against said bar in a direction to move the same into the path of said tappet.
- 60 18. A bell ringing mechanism comprising an operating bar operatively connected with a bell sounding device, a movable tappet engaging said bar and moving the same downwardly for sounding said sounding device, a detent device which holds said bar laterally out of the path of said tappet, a shifting device for moving said bar laterally into the path of said tappet when released by said detent device, a disengaging 65 device for moving said bar out of engagement from said tappet, means for moving said bar upwardly when released from said tappet, and a guide which is engaged on its front side by said bar during the downward movement thereof and on its rear side during the upward movement of the same.
- 70 19. A bell ringing mechanism comprising an operating bar operatively connected with a bell sounding device, a movable tappet 75 engaging said bar and moving the same downwardly, for sounding said sounding device, a detent device which holds said bar laterally out of the path of said tappet, a shifting device for moving said bar laterally into the path of said tappet when released by said detent device, a disengaging device for moving said bar out of engagement from said tappet, means for moving said bar upwardly when released from said tappet, and a guide which is engaged on its front side by said bar during the downward movement thereof and on its rear side during the upward movement of the same, said bar having a beveled lower edge and 80
- 85 110 105 115 120 125 130

said guide having a beveled upper edge adapted to be engaged by the beveled edge of said bar during the descent of the latter.

20. A bell ringing mechanism comprising
 5 an operating bar operatively connected with a bell sounding device, a movable tappet engaging said bar and moving the same downwardly, a detent device which holds said bar laterally out of the path of said tappet, a shifting device for moving said bar laterally into the path of said tappet when released by said detent device, a disengaging device for moving said bar out of engagement from said tappet, means for moving
 10 said bar upwardly when released from said tappet, a guide which is engaged on its front side by said bar during the downward movement thereof and on its rear side during the upward movement of the same, said
 15 guide having a fixed section and a movable section for permitting of utilizing either the full length of the same when a long bell operating stroke of the bar is desired or only part of the length of the same when a
 20 short bell operating stroke of the bar is desired.
21. A bell ringing mechanism comprising an operating bar operatively connected with a bell sounding device, a movable tappet engaging said bar and moving the same downwardly, a detent device which holds said bar laterally out of the path of said tappet, a shifting device for moving said bar laterally into the path of said tappet when released by said detent device, a disengaging device for moving said bar out of engagement from said tappet, means for moving
 25 said bar upwardly when released from said tappet, a guide which is engaged on its front side by said bar during the downward movement thereof and on its rear side during the upward movement of the same, said guide having a fixed upper section and a lower laterally movable section, a latch for holding said movable guide section in line with the fixed section, and means for releasing said latch from said movable guide section comprising an electro-magnet 90 having an armature connected with said latch, and a switch for opening and closing the electric circuit containing the coil of said electro-magnet.
24. A bell ringing mechanism comprising
 95 an operating bar operatively connected with a bell sounding device, a movable tappet engaging said bar and moving the same downwardly, a detent device which holds said bar laterally out of the path of said tappet, a shifting device for moving said bar laterally into the path of said tappet when released by said detent device, a disengaging device for moving said bar out of engagement from said tappet, means for moving
 100 said bar upwardly when released from said tappet, a guide which is engaged on its front side by said bar during the downward movement thereof and on its rear side during the upward movement of the same, said guide having a fixed upper section and a lower laterally movable section, a latch for holding said movable guide section in line with the fixed section, and means for releasing said latch from said movable guide section comprising an electro-magnet 95 having an armature connected with said latch, and a switch for opening and closing the electric circuit containing the coil of said electro-magnet.
25. A bell ringing mechanism comprising
 105 a bell, a hammer movable toward and from said bell, a cushion member movable into and out of the path of said hammer, and an operating rod connected with said hammer and cushion member for moving the same in unison.
26. A bell ringing mechanism comprising
 110 a bell, a hammer movable toward and from said bell, a cushion member movable into and out of the path of said hammer, an operating rod connected with said hammer and cushion member so that a short stroke of the operating rod causes the hammer to 115
- 120
- 125
- 130

strike the bell indirectly while the cushion member is still interposed between said hammer and bell but a long stroke of the operating rod causes the cushion member to

5 clear the path of the hammer and permits the latter to strike the bell directly.

27. A bell ringing mechanism comprising a bell, a hammer movable toward and from said bell, a cushion member movable into 10 and out of the path of said hammer, an operating rod connected with said hammer and

cushion member for moving the hammer toward the bell and the cushion member downwardly, and a spring for raising the cushion member.

Witness my hand this 19th day of June, 1914.
